UNITED STATES PATENT OFFICE.

WILLIAM E. MAGARRELL, OF LOS ANGELES, CALIFORNIA, ASSIGNOR TO ALWAYS READY IRONING BOARD CO., OF LOS ANGELES, CALIFORNIA, A CORPORATION OF CALIFORNIA.

COMBINED TABLE AND IRONING-BOARD.

1,270,184.

Specification of Letters Patent. Patented June 18, 1918.

Application filed October 10, 1916. Serial No. 124,913.

To all whom it may concern:

Be it known that I, WILLIAM E. MAGARRELL, a citizen of the United States, residing at Los Angeles, in the county of Los Angeles and State of California, have invented a new and useful Combined Table and Ironing-Board, of which the following is a specification.

My invention relates to the art of building construction.

The principal object of the invention is to provide as a household convenience a combined table and ironing board, this table and ironing board being so constructed that either the table or the ironing board can be used, as desired.

A further object of the invention is to provide a structure which will take up very little space and which will present a good appearance, so that it can be incorporated in high priced dwellings.

A still further object of the invention is to provide a structure which will be easy to adjust and which will be very firm and rigid when adjusted.

A still further object of the invention is to provide a structure which will have as small a number of parts as possible so that the cost of construction will not be excessive.

A still further object of the invention is to provide a structure which will be so constructed that there is no danger of its getting out of order.

Further objects and advantages will be set forth hereinafter or will be evident to one skilled in the art, from an inspection of the accompanying drawings and its explanatory specification.

Referring to the drawing which is for illustrative purposes only:

Figure 1 is a perspective view of my invention in the form it assumes when not in use.

Fig. 2 is a view of my invention with the upper door opened to show how the table and ironing board fit into the case when not in use.

Fig. 3 is a view showing the table extended into the position it occupies when in use.

Fig. 4 is a perspective view showing the ironing board in the extended position it occupies when in use.

Fig. 5 is a detail, on an enlarged scale,

showing the inner ends of the ironing board and table, in the position they assume when the ironing board is in its extended position.

In the embodiment of my invention shown in the drawing, a casing 11 is provided, this casing being ordinarily in the form of a box having an open front and of such dimensions that it will readily fit into the wall between the studding of any of the ordinary types of dwellings. The casing 60 11 is provided with an upper door 12 which is provided with hinges 13 by which it may be swung open, as shown in Fig. 2. A lower door 14 is provided with hinges 15 by which it may swing open, as shown in Figs. 70 3 and 4.

The door 14 is provided with hinges 16 at its upper end, these hinges being secured to a table 17. The table 17 has leaves 18 secured on either side thereof by means 75 of hinges 19, a cross bar or brace 20 being provided under the table and mounted on the pin 21 so that it can be swung out to support the leaves 18 in their open position, as shown in Fig. 3.

The inner end of the table 17 is provided with a pin 22 which slides in a front slot 23 formed in the inner wall of the casing 11, this front slot 23 terminating in a lower notch 24, as best illustrated in Fig. 5. 80

An ironing board 26 is provided with a pin 27 on its inner end, this pin sliding in back slots 28 formed on either wall of the casing 11 at either side thereof, the back slots 28 terminating in upper notches 90 29. Secured on the under side of the ironing board 26 is a cross bar 30.

The method of operation of the invention is as follows:

The parts being in the position shown in 95 Fig. 1, the doors 12 and 14 being open, if it is desired to use the table, which is standing vertically inside the casing 11 with the pin 22 in the bottom of the front slot 23 and with the leaves 18 in their closed position, the table 17 is pulled upwardly and outwardly, the pin 22 sliding in the front slot 23 and the door 14 falling forward. When the table 17 assumes a horizontal position, the pin 22 enters the lower notch 24 which 100 will thereafter support the inner end of the table. The brace 20 is then turned into the position shown in Fig. 3, and the leaves 18 are opened out into the position shown in that figure. With the table in this position 105 110

it forms a very rigid and convenient appliance, being especially adapted for use in kitchens where the space is somewhat limited.

- 5 When it is desired to use the ironing board, the ironing board is pulled up, the pin 27 sliding in the slot 28 until the ironing board assumes a horizontal position at which time the pin 27 slides into the upper 10 notch 29, which thereafter supports the inner end of the ironing board. The table 17 is then pulled up without opening the leaves 18 until the outer end thereof rests against the inside of the cross bar 30 and the pins 15 31 on the cross bar 30 engage holes 32 in the leaves 18, securely locking the ironing board and table together against lateral displacement. The parts then assume the position shown in Figs. 4 and 5. In this position the table 17 is not quite horizontal and it forms a very rigid brace for the ironing board 26. Whenever either the table or the ironing board is in its extended position the door 12 may be closed if desired, as shown 20 25 in Figs. 3 and 5.

I claim as my invention:

1. A combined ironing board and table comprising a casing having front slots and back slots formed therein at either side 30 thereof; an ironing board having pins at either side of one end so located that they will slide in said back slots; a table having pins at either side thereof so located that they will slide in said front slots; an upper 35 door closing the upper portion of the front of said casing; a lower door closing the lower portion of front of said casing; hinges connecting the bottom of said lower door with the lower portion of said casing; hinges 40 connecting the top of said door with said table; and means by which said table supports said ironing board in its extended position.

2. A combined ironing board and table comprising a casing having front slots and back slots formed therein at either side thereof; an ironing board having pins at either side of one end so located that they will slide in said back slots; a table having 45 pins at either side thereof so located that they will slide in said front slots; an upper door closing the upper portion of the front of said casing; a lower door closing the lower portion of front of said casing; hinges 50 connecting the bottom of said lower door with the lower portion of said casing; hinges connecting the top of said door with said table; and a cross bar secured to the under side of said ironing board in such a position 55 as to be engaged and supported by the outer edge of said table.

3. A combined ironing board and table comprising a casing having front slots and back slots formed therein at either side 60 thereof; an ironing board having pins at

either side of one end so located that they will slide in said back slots; a table having pins at either side thereof so located that they will slide in said front slots; means for supporting the inner end of said ironing board in its extended position; an upper door closing the upper portion of the front of said casing; a lower door closing the lower portion of front of said casing; hinges connecting the bottom of said lower door with the lower portion of said casing; hinges connecting the top of said door with said table; and means by which said table supports said ironing board in its extended position.

4. A combined ironing board and table comprising a casing having front slots and back slots formed therein at either side thereof; an ironing board having pins at either side of one end so located that they will slide in said back slots; a table having pins at either side thereof so located that they will slide in said front slots; means for supporting the inner end of said ironing board in its extended position; an upper door closing the upper portion of the front of said casing; a lower door closing the lower portion of front of said casing; hinges connecting the bottom of said lower door with the lower portion of said casing; hinges connecting the top of said door with said table; and a cross bar secured to the under side of said ironing board in such a position as to be engaged and supported by the outer edge of said table.

5. A combined ironing board and table comprising a casing having front slots and back slots formed therein at either side thereof; an ironing board having pins at either side of one end so located that they will slide in said back slots; a table having pins at either side thereof so located that they will slide in said front slots; leaves folding over the top of said table when said table is folded into said casing; means for supporting said leaves in an extended position when said table is in an extended position; an upper door closing the upper portion of the front of said casing; a lower door closing the lower portion of front of said casing; hinges connecting the bottom of said lower door with the lower portion of said casing; hinges connecting the top of said door with said table; and means by which said table supports said ironing board in its extended position.

6. A combined ironing board and table comprising a casing having front slots and back slots formed therein at either side thereof; an ironing board having pins at either side of one end so located that they will slide in said back slots; a table having pins at either side thereof so located that they will slide in said front slots; leaves folding over the top of said table when said

- table is folded into said casing; means for supporting said leaves in an extended position when said table is in an extended position; an upper door closing the upper portion of the front of said casing; a lower door closing the lower portion of front of said casing; hinges connecting the bottom of said lower door with the lower portion of said casing; hinges connecting the top of said door with said table; and a cross bar secured to the under side of said ironing board in such a position as to be engaged and supported by the outer edge of said table.
- 15 7. A combined ironing board and table comprising a casing having front slots and back slots formed therein at either side thereof; an ironing board having pins at either side of one end so located that they will slide in said back slots; a table having pins at either side thereof so located that they will slide in said front slots; leaves folding over the top of said front slots; leaves folding over the top of said table when said table is folded into said casing; means for supporting said leaves in an extended position when said table is in an extended position; means for supporting the inner end of said ironing board in its extended position; an upper door closing the upper portion of the front of said casing; a lower door closing the lower portion of front of said casing; hinges connecting the bottom of said lower door with the lower portion of said casing; hinges connecting the top of said door with said table; and a cross bar secured to the under side of said ironing board in such a position as to be engaged and supported by the outer edge of said table.
- 20 8. A combined ironing board and table comprising a casing having front slots and back slots formed therein at either side thereof; an ironing board having pins at either side of one end so located that they will slide in said back slots; a table having pins at either side thereof so located that they will slide in said front slots; leaves folding over the top of said front slots; leaves folding over the top of said table when said table is folded into said casing; means for supporting said leaves in an extended position when said table is in an extended position; means for supporting the inner end of said ironing board in its extended position; an upper door closing the upper portion of the front of said casing; a lower door closing the lower portion of front of said casing; hinges connecting the bottom of said lower door with the lower portion of said casing; hinges connecting the top of said door with said table; and a cross bar secured to the under side of said ironing board in such a position as to be engaged and supported by the outer edge of said table.
- 25 9. A household convenience comprising a cabinet adapted to be secured to a wall; a table of proper width to fold inside said cabinet; means for detachably securing one end of said table in said cabinet; leaves hinged to the side of said table; means for supporting said leaves in their extended position; means for supporting the other end of said table with relation to said cabinet; an ironing board of proper size to be contained entirely within said cabinet; and means by which said table supports said ironing board when it is extended.
- 30 10. A built in the wall appliance comprising a cabinet of suitable size and shape to be secured in a wall between the studding thereof; a table element of proper size and shape to fold entirely inside of said cabinet; means for guiding the inner end of said table so that it can slide up and down in said cabinet; supports at the inner end of said table by which said end can be secured with relation to said cabinet when said table element is extended in a horizontal position; a door closing the front of said cabinet when said table element is folded therein; means by which said door supports the outer end of said table element when said table element is extended in a horizontal position; an extensionable leaf hinged to one side of said table element in such a manner that it can be folded into a parallel plane with said table element and thus folded into said cabinet; and means for supporting said leaf in the same plane as said table element.
- 35 In testimony whereof, I have hereunto set my hand at Los Angeles, California, this 3rd day of October, 1916.
